UNITED STATES PATENT OFFICE.

CATHARINE L. DARBY, OF STAMFORD, CONNECTICUT.

CLOTHING-PROTECTOR.

SPECIFICATION forming part of Letters Patent No. 462,965, dated November 10, 1891.

Application filed February 2, 1891. Serial No. 379,870. (No model.)

To all whom it may concern:

Be it known that I, CATHARINE L. DARBY, a citizen of the United States, residing at Stamford, in the county of Fairfield and State of Connecticut, have invented certain new and useful Improvements in Clothing-Protectors; and I do hereby declare the following to be a full, clear, and exact description of the invention, such as will enable others skilled in the art to which it appertains to make and use the same.

My invention has for its object to provide a simple, inexpensive, and comfortable article to be worn by ladies as a protector for under-clothing, bedclothing, &c.

It is of course well understood that at certain periods it is necessary for ladies to take great pains to protect their clothing, and that for this purpose napkins, absorbent-pads, and various other devices are worn. With the greatest care, however, as these devices have heretofore been constructed it is not infrequent that in moving about, and also while sleeping, the clothing becomes soiled and not infrequently ruined by staining.

In order to wholly avoid accidents of this sort, and thereby give to the wearer a feeling of perfect safety at all times, I have devised the novel protector which I will now describe, referring by numerals to the accompanying drawings, forming part of this specification, in which—

Figure 1 is an elevation of my novel protector complete; Fig. 2, a section on the line $\alpha\alpha$ in Fig. 1; and Fig. 3 is a diagram on a reduced scale, showing the shape of the single piece of cloth from which the body portion of the protector is made.

1 denotes the body portion, which may be made of any suitable water-proof material—as, for instance, light rubber cloth or oiled silk, or muslin. I preferably, however, use the grade of rubber cloth commonly known as "stockinet" rubber cloth, which is used so extensively in the manufacture of the better grade under-arm shields. The body portion is made large enough so as to pass freely over the hips, and in use is closed tightly, except at the waist, where it is secured by a suitable string or band 2. (See dotted lines, Fig. 1.) This string or band may be run into the top of the body portion itself, or may be held by

loops 3, as shown in the drawings. 4 denotes strong elastic bands at the leg-openings, which in use close tightly about the thighs.

It will of course be understood that it is absolutely essential that the body portion should be full between the legs, and that that portion should be wholly free from seams. I therefore cut out the pieces of material from which the protectors are made to substantially the form illustrated in Fig. 3, the portions marked $\alpha\alpha$ being at the waist when the protector is made up, and the portions marked $\beta\beta$ being joined together preferably by cemented seams at the side. At opposite sides of the piece the material is cut away, as at $\gamma\gamma$, leaving rounded openings, which, when the sides are joined together, constitute leg-openings, around which the strong elastic leg-bands 4 are firmly attached, preferably by cementing. The result is that in the completed protector there is a fullness, as at 5, between the leg-bands. At the top of the body portion at front and back I place straps 6, (see dotted lines, Fig. 1, also shown in section in Fig. 2,) which are preferably provided with buckles, and which may or may not be made elastic. These straps constitute the support for the napkin 7.

In practice I preferably use an endless napkin, as clearly shown in Fig. 2, which may be made wide enough to form two or more folds, as may be preferred. It will be seen that my novel protector provides a perfect safeguard against soiling the clothing and renders it practically impossible for accidents to happen. The napkin may be adjusted to the required tightness by means of straps 6. The fullness at 5 is ample to receive the napkin 9c without the slightest inconvenience to the wearer. It should be noticed, furthermore, that at each end of fullness 5 the material of the body portion is drawn up close to the trunk of the wearer by the leg-bands, so that even should the napkin become saturated the water-proof character of the body portion and the special manner in which the protector is made and held in place insure practically absolute protection to the clothing of the wearer. 100

Having thus described my invention, I claim—

1. A clothing-protector the body portion of which is made from a single piece of water-

proof material secured together by seams at the sides, substantially as described and shown, said protector being provided with leg-openings having elastic bands 4, which hold the protector tightly about the thighs, leaving a fullness 5 between said leg-bands and being provided at front and back with straps 6 for the attachment of the napkin.

2. A clothing-protector the body portion of which consists of a piece of water-proof material having cut-away portions at opposite sides to form leg-openings, said sides being

joined together, as described, elastic bands 4 about the leg-openings, which close the material tightly about the thighs, leaving a fullness 5, straps 6 for the attachment of a napkin, and a band 2 by which it is held in place. 15

In testimony whereof I affix my signature in presence of two witnesses.

CATHARINE L. DARBY.
